UNITED STATES PATENT OFFICE.

CONRAD F. GRAFT, OF ST. LOUIS, MISSOURI.

RAILROAD-RAIL.

No. 811,055.

Specification of Letters Patent.

Patented Jan. 30, 1906.

Application filed May 8, 1905. Serial No. 259,364.

To all whom it may concern:

Be it known that I, CONRAD F. GRAFT, a citizen of the United States, residing at St. Louis, in the State of Missouri, have invented 5 a new and useful Improvement in Railroad-Rails, of which the following is a specification.

This invention relates to a rail in which a base and a tread section are employed, the 10 two overlapping.

The object of the invention is a rail in which the tread-section when worn or broken can be readily replaced without replacing the 15 complete rail, the new tread being set in position upon the old base.

Another object is a rail in which the use of nuts and the usual form of fish-plates is avoided.

The invention consists in the novel features of construction hereinafter described, 20 shown in the accompanying drawings, and pointed out in the claims.

In the drawings, Figure 1 is a perspective view of my rail, one base-section being 25 broken off. Fig. 2 is a perspective view of an end portion of a base-section. Fig. 3 is an inverted perspective view of a portion of a tread-section, showing a tie-block in place and also inverted. Fig. 4 is a perspective 30 view of the tie-plates used in connection with the block. Fig. 5 is a perspective view of a bolt.

In the drawings, A represents the base-section of the complete rail, and B the tread-section. Hereinafter these parts will be referred to simply as the "base" and "tread." 35 The base is grooved along its upper face, as shown at A'. At each end the base is cut away, as shown at A³, and recesses are formed in the sides adjacent the ends, as at A⁴. Perforations A² are formed in the sides of the base above the bottom of the groove A' for the passage of bolts C.

The tread B has a central depending web 45 B', perforated for passage of the bolts C, as shown at B², and the tread A also carries on each side depending flanges B³, which fit over the sides of the base A, the web B' fitting in the grooves A' of the bases, as it will be understood that in assembling the rail the tread and base break joints. A block D is bifurcated to straddle the web B' of the tread and is reduced in thickness adjacent its longitudinal center by being cut away on the sides,

as shown at D'. The blocks D rest on the 55 base A adjacent each end of the base and in the cut-out portions A³, the cut-away portions D' of the blocks alining with the recesses A⁴ of the base. Plates E, forming tie-plates, fit in the cut-away portions of the 60 blocks and in the recesses A⁴ of the base, one end of each plate resting in a recess A⁴ of one base and the other end of the block in a similar recess in the adjacent base. One plate E of each pair carries on its inner face an integral 65 pin E', which passes through a suitable perforation in the block D and through an alining perforation in the other or opposing plate of the pair and is locked in position by a cotter-pin E². The bolts C after being placed in 70 position have one end angled or bent, as shown at C' in Fig. 5.

Having thus fully described my invention, what I claim as new, and desire to secure by Letters Patent, is—

1. A rail comprising overlapping tread and base sections, the base-sections being cut out at the ends and recessed on the sides, a block fitting said cut-out portions and recessed on the sides, plates fitting said recesses, each 80 plate overlapping the block, and means for locking the plates in position.

2. A rail comprising a tread having a depending web, a base longitudinally grooved to receive the web, said base being recessed 85 on each side adjacent the ends, a block adapted to fit between two base-sections, and recessed on the sides, said block being bifurcated to straddle the web, and tie-plates fitting in the recesses of the bases and block. 90

3. A rail of the kind described comprising a tread portion having a depending web and depending side flanges, a base cut away at each end and grooved to receive the web, said base and tread having alining perforations, a bolt 95 adapted to pass through said perforations, a block adapted to fit in the cut-out portions of adjoining bases, said block and bases having alining recesses, a tie-plate adapted to fit said recesses and having an integral pin 100 adapted to pass through the block, an opposing tie-plate perforated for the passage of the pin, and means for locking the pin in place.
